UNITED STATES PATENT OFFICE.

OBED W. BARNARD, OF SENECA, KANSAS.

WASHING-MACHINE.

SPECIFICATION forming part of Letters Patent No. 317,486, dated May 12, 1885.

Application filed May 27, 1884. (No model.)

To all whom it may concern:

Be it known that I, OBED W. BARNARD, a citizen of the United States, residing at Seneca, in the county of Nemaha and State of 5 Kansas, have invented a new and useful Washing-Machine, of which the following is a specification, reference being had to the accompanying drawings.

This invention has relation to washing-machines; and it consists in the construction and novel arrangement of parts, as will be hereinafter fully described, and particularly pointed out in the claims.

Figure 1 is a view in perspective of a washing-machine embodying my improvements. Fig. 2 is a plain view of the suds-box with the lid removed. Fig. 3 is a vertical longitudinal section through the middle of the machine. Fig. 4 is a view in perspective of the auxiliary 20 suds-box removed from the main suds-box; and Fig. 5 is a bottom perspective of the agitator.

Referring by letter to the accompanying drawings, A designates the suds-box of the washing-machine, which is rectangular in form 25 and is of the ordinary size in general use. The inner faces of the sides of the suds-box A are provided with horizontal cleats B B' B², near its upper edge having spaces C C between them. The inner faces of the sides of the suds-box A are also provided with vertical cleats D D, the inner edges of which are aligned with the inner ends of the horizontal cleats B B². These vertical cleats D D form guides and 30 stays for the projecting ends of the side boards of an auxiliary suds-box, E, which is removably fitted into the suds-box A. The suds-box A is provided with a hinged lid, G, having the gearing which drives the agitator-shaft 35 attached thereto.

The agitator-shaft H passes through a bearing in the base-plate I, secured to the lid G, and through a hole in the lid into the suds box A, or into the auxiliary suds-box E when the latter is in its place in the suds-box A. The lower end of the agitator-shaft is provided with the agitator J, which consists of a circular wooden plate, K, having four rectangular grooves, L, extending from near its central 45 opening, through which the dasher-shaft is passed, to the edges of the plate K, to form the seats for the galvanized-iron agitator arms 50

or stirrers M, which are bent as shown, and are about three-eighths of an inch in thickness, so that they will pass through the water more 55 easily than if they were thicker. The upper end of the agitator-shaft J is provided with a pinion, N, the lower side of which bears upon the upper face of base-plate I. The base-plate I is provided with a post, O, having a bearing, P, at its upper end for the shaft Q of the oscillating segmental gear-wheel R, the teeth S of which engage the teeth of the pinion N. The face of the gear-wheel R is flat where the teeth S are located, and not beveled, as is customary in this class of machines. On the same 60 face with the teeth S, at the middle of the upper half of the gear-wheel R, is a tapering recess, T, provided with a bolt-hole, U. The lower end of the handle V rests in this recess 65 T, and is secured in place by a bolt passed through a hole in the handle and through the bolt-hole U. The gear-wheel R is strengthened at its middle by an integral transverse bar, W, and below this it is open, as shown 70 at X, to render it as light as possible without detracting from its strength.

When a full-sized or ordinary washing is to be done, the suds-box A is used, but when only a small-sized washing is to be done the auxiliary suds-box E is put in place, and but a small quantity of water needs to be heated, as it is not necessary to fill the main suds-box. This gives the machine a decided advantage 80 over other washing-machines, as in all of them 85 a large quantity of water has to be heated even to wash a few small articles, which causes a waste of time and fuel in many instances, and especially in the summer season when fires are not kept going.

When the auxiliary suds-box is removed, the rotation of the agitator in the main suds-box creates a current in the water therein, and this current of water circulates the clothes 95 around in the suds-box so that every article in turn will be grasped and whirled around in the water by the agitator, and thus all the clothes will be washed.

Having thus fully described my invention, what I claim as new, and desire to secure by 100 Letters Patent of the United States, is—

1. The combination, with the suds-box A, having the horizontal cleats B B' B² near the upper edges on the inner faces of its sides, the

spaces C C, and the vertical cleats D D, of the auxiliary suds-box having its side boards projected at the ends of said suds-box, substantially as specified.

- 5 2. The combination of the suds-box A, having the hinged lid G, the horizontal cleats B B', near the upper edges on the inner faces of its sides, the spaces C C, and the vertical cleats D D, the base-plate I, secured to the 10 hinged lid, and having the post O, the oscillating gear-wheel R, having handle V, the agitator-shaft H, having pinion N engaging with

gear-wheel R, and the plate K, having stirrers M, and the auxiliary suds-box having its side boards projecting at the ends, substantially as 15 described.

In testimony that I claim the foregoing as my own I have hereto affixed my signature in presence of two witnesses.

OBED W. BARNARD.
